UNITED STATES PATENT OFFICE.

ANGELO JOSEPH MORNAGHINI, OF BROOKLYN, NEW YORK.

DESIGN FOR A SMOKER'S ASH RECEPTACLE OR SIMILAR ARTICLE.

Application filed July 20, 1928. Serial No. 27,544. Term of patent 3½ years.

To all whom it may concern:

Be it known that I, ANGELO J. MORNAGHINI, a citizen of the United States, and a resident of New York city, borough of Brooklyn, in the county of Kings and State of New York, have invented a new, original, and ornamental Design for a Smoker's Ash Receptacle or Similar Article, of which the following is a specification.

Reference is had to the accompanying drawing forming part thereof.

Figure 1 is a plan view of a smoker's ash receptacle or similar article, showing my new design.

Fig. 2 is a side elevation.

I claim:

The ornamental design for a smoker's ash receptacle or similar article, as shown.

Signed at New York in the county of New York and State of New York this 19th day of July, A. D. 1928.

ANGELO JOSEPH MORNAGHINI.
